UNITED STATES PATENT OFFICE.

HERMANN CARRI, OF NEW YORK, N. Y.

DUPLEX SCISSORS.

Application filed June 4, 1927. Serial No. 196,435.

This invention relates to duplex scissors and has for an object to provide simple and efficient means for adjusting the lateral spacing of the two pairs of blades as well as to arrange the operating handles in such manner that the same force is applied to both pairs of blades.

In one embodiment of the invention, two pairs of scissors blades are mounted upon a single threaded axle. One pair of blades is arranged at one end of the axle and is held against axial movement. The other pair of blades is rotatably mounted upon a sleeve which is interiorly threaded to co-operate with the threads of the axle. The two pairs of blades are operated in unison through the medium of members extending between corresponding blades. These members are rigidly connected to one pair of blades and slidably connected to the other. A handle is attached to each member intermediate the blades. A post is rigidly connected to one blade of the first pair and extends through the corresponding blade of the other pair. This post is threaded to cooperate with the threads of a sleeve rotatably mounted in a blade of the second pair and through which the post extends. This sleeve, as well as the sleeve through which the axle extends, is provided with pinions which mesh with a third pinion rotatably mounted on the blade through which the post extends and which is provided with a knurled button by means of which it may be rotated. Rotation of the third pinion causes rotation of the sleeves, thereby moving the second pair of blades toward or away from the first pair of blades.

Duplex scissors of this character are useful wherever it is desired to make two cuts simultaneously. They may be designed for cutting paper, cloth and the like or for cutting tin, leather and the like. They may also be used for cutting surgical bandages either straight or circular. The two sets of blades may be moved toward or away from each other through the operation of a single adjusting member. Moreover, since the handles are arranged between the two pairs of blades, equal force is applied to each pair.

Other objects, novel features and advantages of the invention will be apparent from the following specification and accompanying drawings wherein

Figure 1 is a side elevation of duplex scissors embodying the invention, and

Fig. 2 is an end elevation thereof.

10 and 10^a designate one pair of blades while 11 and 11^a designate the second pair 60 of blades. Both sets of blades are pivotally mounted upon the screw-threaded axle 12. The blades 10 and 10^a are arranged at one end of the axle 12 and are fixed against axial movement thereof, while the blades 11 65 and 11^a are mounted upon a sleeve 13 which is interiorly threaded to co-operate with the threads on the axle 12. A threaded post 14 is rigidly connected to the blade 10 and passes through a sleeve 15 mounted in the 70 blade 11. The post 14 and sleeve 15 are provided with co-operating screw threads. A pinion 16 is connected to the sleeve 13 and a pinion 17 is connected to the sleeve 15. These pinions mesh with a third pinion 18 75 rotatably supported by the blade 11 and provided with a knurled button 19 by means of which it may be operated.

Upon each of the blades 10 and 10^a is rigidly mounted a plate 20, each of the 80 plates being slotted as at 21. Each of the blades 11 and 11^a is provided with a pin 22 which projects into the slot 21 and is provided with a head which overlies the edges of the slot. Handle members 23 are attached to the plates 20 intermediate the ends thereof. By virtue of this arrangement of the handles, equal force is applied to each pair of blades.

The lateral relationship of the two pairs 90 of blades may be varied by rotating the pinion 18. Rotation of this pinion causes rotation of the pinions 16 and 17 together with the sleeves 13 and 15, thereby causing the blades 11 and 11^a to move toward or 95 away from the blades 10 and 10^a. When the blades 11 and 11^a are thus moved, the pins 22 move longitudinally of the slots 21.

It is apparent that the invention may be embodied in scissors designed for the cutting of different materials and that they may be made of any desired size. Moreover, it is apparent that various modifications may be made in the structural details without in any way departing from the 105 spirit of the invention as defined in the appended claims.

I claim:

1. In combination, an axle, a pair of blades mounted on said axle at one end 110

thereof, a sleeve mounted on said axle, said sleeve and axle having co-operating threads, a second pair of blades mounted on said sleeve, a post carried by one of said first 5 pair of blades and passing through the corresponding blade of the second pair, a sleeve mounted in said last-named blade and being interiorly threaded to co-operate with said post, and means for simultaneously rotating both of said sleeves whereby said second pair of blades may be adjusted relative to said first pair of blades.

2. In combination, a threaded axle, a pair of blades mounted upon said axle at one end thereof, a threaded sleeve mounted on said axle, a pair of blades mounted on said sleeve, a pinion connected to said sleeve, and a second pinion rotatably mounted upon one blade of said second pair.

20 3. In combination, a threaded axle, a pair of blades mounted upon said axle at one end thereof, a threaded sleeve mounted on said axle, a pair of blades mounted on said sleeve, a pinion connected to said sleeve, a second 25 pinion rotatably mounted upon one blade of said second pair, a threaded post carried by one of the first pair of blades, a threaded sleeve mounted in the corresponding blade of the second pair and through which said 30 post extends, and a third pinion rotatably mounted upon said last-named blade and being in mesh with each of said other pinions.

4. In combination, a threaded axle, a pair 35 of blades mounted upon said axle at one end thereof, a threaded sleeve mounted on said axle, a pair of blades mounted on said sleeve, a pinion connected to said sleeve, a second pinion rotatably mounted upon one blade of 40 said second pair, a threaded post carried by one of the first pair of blades, a threaded sleeve mounted in the corresponding blade of the second pair and through which said 45 post extends, a third pinion rotatably mounted upon said last-named blade and being in mesh with each of said other pinions, plates rigidly connected to one pair of blades and slidably connected to the other

pair of blades, and handles mounted on said plates intermediate said blades. 50

5. In combination, two pairs of cutting blades mounted on a common axle, means for varying the lateral spacing of the pairs of blades comprising a sleeve supporting one pair of blades and threaded to said axle, means to rotate said sleeve, plates rigidly connected to one pair of blades and slidably connected to the corresponding blades of the other pair and handles mounted on said plates intermediate said pairs of blades. 55

6. In combination, two pairs of cutting blades mounted on a common axle, a guide post carried by one blade of one pair and extending through the corresponding blade of another pair, means for varying the lateral spacing of the pairs of blades comprising sleeves threaded on said axle and guide post, one of said sleeves supporting one pair of blades and the other sleeve being mounted in one blade of said pair, means for rotating said sleeves, plates rigidly connected to one pair of blades and slidably connected to the corresponding blades of the other pair and handles mounted on said plates intermediate said pairs of blades. 60

7. In combination, two pairs of blades mounted on a common axle, slotted plates mounted on the blades of one pair, pins mounted on the blades of the other pair and arranged in the slots of said plates, means for varying the lateral spacing of said blades comprising a sleeve supporting one pair of blades and threaded to said axle, and means to rotate said sleeve. 75

8. In combination, two pairs of blades 80 mounted on a common axle, a pair of plates rigidly connected to one pair of blades and slidably connected to the other pair, and means for varying the lateral spacing of said pairs of blades comprising a sleeve supporting one pair of blades and threaded to said axle, and means to rotate said sleeve. 85

In testimony whereof, I have signed my name to this specification.

HERMANN CARRI.
